UNITED STATES PATENT OFFICE.

ABIJAH S. PARKER, OF CINCINNATI, OHIO.

PROP FOR CARRIAGE-TOPS.

SPECIFICATION forming part of Letters Patent No. 269,878, dated January 2, 1883.

Application filed January 30, 1882. (Model.)

To all whom it may concern:

Be it known that I, ABIJAH S. PARKER, a citizen of the United States, residing at Cincinnati, Hamilton county, Ohio, have invented 5 certain new and useful Improvements in Props for Carriage and Buggy Tops, of which the following is a clear, full, and exact description.

My invention relates to that class of top-props in which the bolt or stem on which the 10 prop-joint is pivoted is passed through the bow. The novelty of my invention consists in the combination, with the bow and the bolt inserted therethrough, of separate clips embracing the bow on both sides and edges and held 15 in place by the bolt, whereby the bow is prevented from splitting and the bolt from turning therein; also, in an improved device for preventing the displacement of the stay-nut, all as will be herewith set forth and specifically 20 claimed.

In the accompanying drawings, Figure 1 is a side elevation of a prop, showing a modification of my invention. Fig. 2 is a central longitudinal sectional view of Fig. 1. Fig. 3 is an 25 enlarged plan view of the nut-locking washer. Fig. 4 is a sectional view, showing the application of my improved prop. Fig. 5 is a detail sectional view, showing a second modification of my improvement.

30 The props hitherto in use have either been fastened to the bows by means of plates screwed thereon, into sockets of which the bolt or stem was screwed without passing through the bow, or else the bolts were formed with integral T-shaped heads, which, when the bolts were inserted through the bow embraced the same on its edges to prevent the splitting of the bow. The objection of the first of these constructions is that the screws which hold the plate are liable to work loose or pull out; and to the second construction the objection is that there is 35 difficulty in forming the T-shaped heads integral with the bolts and making them the proper size. A further objection to both forms is that the bolt has to be secured to the bow before the top lining and cover are applied, and in applying the latter it is a difficult matter to cut the holes in the proper place in the cover for the bolt to extend through.

40 To remedy these difficulties and at the same time obtain all the advantages of strength and cheapness, I have devised the construction

shown in Fig. 4, where A is the bolt, B the bow, and *a a* the embracing-clips, one of which is shown in perspective to the right of Fig. 4. 55 These clips are made of wrought-iron struck up and centrally perforated, as shown, and of sufficient size to snugly embrace the bow on its edges, as shown. When applied to the perforated bow, as shown, the lining and cover 60 are applied, and then the bolt is passed through the apertures in the clips, and the perforation in the bow and its head serves to hold one of the clips in place, while the usual thimble, C, Figs. 1 and 2, holds the other. Over the bolt- 65 nut to the thimble is slipped a washer, E, then the prop joint or brace D, and finally the usual stay-nut, F, is screwed over the end, holding all in place.

To prevent the stay-nut F from jarring off or 70 from being turned by the vibration of the prop-joint in its usual operation, I cut away portions of the threaded end of the bolt forming flat recesses on each side thereof, as seen in Figs. 2 and 3, and before screwing on the nut F, I 75 spring a slotted metal washer, G, Figs. 2 and 3, around the recessed portion of the bolt, so that it embraces the flat recesses before mentioned, and cannot be pulled or slip off, owing to the shoulders formed at *f*, where the mouth 80 or opening of the slot is made narrower than the body or rear part thereof. By now screwing on the nut F to its proper place it will be seen that an immovable division is interposed between the nut and the swinging head of the 85 brace D, so that the movement of the latter cannot turn the nut.

If desired, the ends *b* of the washer may be 90 prolonged, as shown in Fig. 3, and may be bent up against the side of the nut, as seen in Fig. 1, thereby preventing the nut from being turned by jarring or other means aside from the action of the brace.

I am aware that slotted washers have been 95 employed as nut-locks; but in such construction the slot in the washer was of uniform width and could be slipped onto and off the bolt without impediment and without springing the washer. In such construction the washer is liable to be misplaced or to slip off. 100

As a modification of my invention the clips *a*, Figs. 1 and 2 and 5, might have enlarged central portions or swells, into which the threaded end of a headless bolt is screwed, as seen;

but I prefer the construction shown in Fig. 4, as the simplest and best. Where the construction shown in Fig. 5 is employed the headless bolt might have a swell or shoulders, *d*, to embrace the outer face of the bow, and also a square or flattened portion, *e*, capable of being gripped by a wrench or spanner to enable the bolt to be easily screwed into the clip *a*.

Having thus fully described my invention, I claim—

1. In a top-prop, the combination, with the bow, of the two separate flanged clips, applied to opposite sides of the bow so as to embrace the same, and the separate removable bolt

passing through the bow and the clips, and 15 susceptible of application after the clips have been applied, substantially as described.

2. In a top-prop, the combination, with the bolt and the brace-joint hung thereon and the stay-nut, of the slotted washer interposed between the brace-joint and the nut, and having the shoulders *f* for preventing its accidental displacement after it is applied, substantially as described.

A. S. PARKER.
